BUFFING WHEEL

John E. Welhaven, Chicago, Ill., assignor to Advance Polishing Wheels, Inc., Chicago, Ill., a corporation of Illinois

Application June 20, 1939, Serial No. 280,051

6 Claims. (Cl. 51—193)

This invention pertains to improvements in buffing wheels and particularly to wheels in which buffing qualities may be controlled by simple and inexpensive means.

5 In abrading the surface of metal objects, such as castings for example, it is customary to apply relatively coarse abradants by means of a polishing wheel so-called. Subsequently, it is necessary to smooth over scratches that may be left by the 10 polishing wheel and to apply a higher polish by means of a buffing wheel.

A distinction is made between polishing wheels and buffing wheels. In polishing wheels, abrading material, such as alundum or carborundum, is glued on the peripheral face of the wheel. The size of the polishing particle glued on the wheel is adapted to the depth of indentations, scratches, or blemishes to be removed from the metal. For example with a sand brass casting that comes from the mold in a rather rough condition, the size of the polishing grain first used is so-called No. 90 which is about the size of granulated sugar. When this has accomplished its preliminary polishing a second polishing cycle is effected by 25 smaller grain abradant glued to the surface of a polishing wheel. Such, for example, is No. 150 grain which is half the size of No. 90 grain. Finally, the casting is smoothed by the polishing wheel sufficiently to be in condition for buffing.

30 The buffing operation not only takes out scratches left by the final operation of the polishing wheel, but also imparts to the work a high luster. The buffing wheel, however, is of different structure from the polishing wheel. The buffing wheel preferably should comprise a relatively loose peripheral face. This face must retain abradant material that is generally in the form of a composition composed of fine powder, a binder and a lubricant rather than granular and 35 generally much softer than alundum or carborundum. Such buffing composition is applied to the rotating buffing wheel face from time to time by the operator. This is in contrast to the polishing wheel of which abradant grains are 40 glued on the face of the polishing wheel. For the buffing wheel the operator applies the buffing composition to the periphery while the wheel is rotating and the composition is taken up by the wheel and held in place until removed by the 45 frictional action of buffing. This composition in commercial practice is usually applied from cakes of suitable size to be held in the operator's hand, for example, a cake 7" x 2" x 2".

An object of this invention is to provide a 50 buffing wheel of suitably open or loose structure

5 at its peripheral face, but also of sufficiently rigid structure to withstand practical shop operations. Another object is to provide a buffing wheel with 10 some flexibility of structure to adapt it for different buffing operations, and also to control the 15 rigidity of the wheel over its central portion inwardly from the buffing peripheral face. An object of particular importance for commercial application is to arrange individual elements of a 20 buffing wheel so as to minimize expense of construction and further so as to permit an operator to utilize elements of the wheel according to the varying needs of individual articles to be polished. A further object is to simplify the 25 structural elements of which a buffing wheel is 30 composed. These and other objects will appear more fully with a description illustrating a structure of buffing wheel that is at present preferred under the present invention. This structure is illustrated in the accompanying drawing and 35 particularly pointed out in the appended claims.

In the drawing:

Figure 1 illustrates a buffing wheel in perspective view showing a buffing face;

Figure 2 shows an enlarged portion of the 25 peripheral face of one form of buffing wheel built up of a plurality of discs constructed according to the present invention and assembled in manner to illustrate the general application of this 30 invention;

Figure 3 shows a structural element comprising 35 radial arms to be embodied within a buffing wheel to impart certain characteristic qualities according to this invention.

In executing the objects of this invention, considerable advantage is gained by assembling a 40 plurality of fibrous discs, between which are inserted radial arms of thicker material preferably of a fibrous nature. Such a wheel may comprise, for example, say 25 cloth discs 1 of convenient 45 diameter, for example, 15 inches. These discs may be of muslin or of other fibrous material. Preferably, the interposed radial arms 2 are joined at their centers to form a disc 3 as in the spider or star-like element illustrated in Figure 3. 50 The cloth discs 1 and interposed radial arms 2 are then stitched together firmly. Preferably, the stitching penetrates through all the discs from center to near the outer face. The stitching may be concentric with the wheel or may be spiral. The stitching, however, is a feature of importance 55 because it serves to control the firmness of the buffing wheel or the density of the cloth elements that make up the structure. The more closely the 55

various lines of sewing occur, the more dense is the buffing wheel.

The material of which the radial arms 2 are composed may conveniently be of canvas or duck and in fact such material is preferred for many purposes because of its firmness combined with its open structure to retain buffing composition. However, for some purposes the interposed arms may be of paper or of cardboard or may be of leather. It must be remembered that in use the buffing wheels are rotated at considerable speed so that there is centrifugal pull. Hence, though open structure discs are desirable for better retention of buffing powder, the elements of the disc must be strong and be strongly secured in order to resist the disintegrating effect of high speed operation.

It will be observed for example from Figure 2 that the structure prepared according to the invention herein described results in a peripheral buffing face 4 in which the flexible elements of which the body is built up present a wavy outline circumferentially of the wheel. The interposed radial ribs press the edges of the adjacent cloth or paper discs laterally. This serves in the first place to produce a wavy circumferential outline but it serves further, when taken with the firmness imparted by stitching the elements and when taken with the rigidity of the radial arms as they extend substantially toward the center of the disc, to introduce a smooth firmness or more closely knit structure in the region of the radial arms. Thus as the wheel rotates against metal to be buffed the wavy outline of the buffing face serves to present the buffing composition with continuously varying angularity. This angularity changes rapidly. But in the portions between adjacent radial arms there are looseness and relative depth that retain considerable buffing composition against the working face of the metal and thus impart what may be determined a softer buffing action. Yet as the wheel moves onward to present to the metal the portions near the radial arms, the abrading action is somewhat harder. The angularity of buffing is changed suddenly where the discs are expanded around the insert arm. Thus the buffing action may be designated as harder where the angular or cross-buffing occurs as the cloth discs are held relatively compactly near the arms. As the wheel is rotated there is rapid alternation of soft action and harder action combined with rapidly changing cross polishing or cross angles of contact between buffing powder and the work.

With buffing elements of the sort described and provided with a central bore, the operator may build up a composite buffing wheel to suit individual requirements. He is able to place the individual elements on a buffing wheel spindle with considerable rapidity. He may place several such wheels side by side, perhaps as many as 10 or 14. A portion of the peripheral face of such a composite buffing wheel is shown in Figure 2. One quickly disposes adjacent discs so that their radial arms occur out of cross alignment with each other. He may interpose different discs of different materials, for example, some of paper and some of cloth, some having canvas radial arms and some having paper or

leather radial arms and thus adapted to receive buffing composition to different degrees and to apply it with different effects of buffing quality.

While a composite disc may be built up by an operator from discs having only one series of radial arms inserted, it is intended under the present invention to include also a plurality of inserted arms within a given disc and stitched firmly to the adjacent cloth elements. Whether the radial arms are inserted separately or whether several discs are inserted, it is preferable that the radial arms be stitched in staggered relation to each other.

In use, buffing discs of the present invention have exhibited superior buffing quality with considerably reduced cost per unit. For example, a series of 500 bumper bars for automobiles were buffed before wearing out a cloth buffing disc containing canvas radial inserts, whereas without the radial inserts the same discs buffed only half as many of the bumper bars before wearing out. Hence, there was an improvement of 100% in life with consequent reduction of cost by one half.

While I have illustrated this invention by reference to the best application now known to me of the problems of this invention, it is now evident that those skilled in this art will be able to introduce deviations from the specific illustrative embodiments herein set forth, but within the scope of the appended claims.

What I claim is:

1. A buffing wheel comprising a plurality of discs of soft sheets secured together with exposed edges forming a soft peripheral face, and inserts of firm fibrous material interposed discontinuously in the peripheral face.

2. A buffing wheel comprising a plurality of discs of soft sheets secured together with exposed edges forming a soft peripheral face and inserts of firm fibrous material interposed as radial arms disposed around the discs and exposed at intervals at the peripheral face.

3. A buffing wheel comprising a plurality of discs of soft sheets secured together centrally with exposed edges forming a soft peripheral face and radial arms of canvas interposed for exposure at intervals at the peripheral face.

4. A buffing wheel comprising a plurality of discs of soft sheets secured together centrally with exposed edges forming a soft peripheral face and interposed discs concentric with the softer discs and comprising radial arms extending for exposure at the peripheral face.

5. A buffing wheel comprising a plurality of discs of soft sheets secured together centrally with exposed edges forming a soft peripheral face and a plurality of concentric discs of fibrous material more dense than the soft discs and disposed in spaced relation to each other and presenting staggered radial inserts in the peripheral face.

6. A buffing wheel comprising a plurality of discs of soft sheets secured together centrally with exposed edges forming a soft peripheral face, and interposed discs concentric with the softer discs and comprising radial arms extending for exposure at the peripheral face, the interposed radial arms being secured by stitching to the adjacent cloth discs.

JOHN E. WELHAVEN.
